(57) **CLAIM**

The ornamental design for a paint brush hook, as shown and described.

DESCRIPTION

FIG. 1 is a front elevational view of our new design for a paint brush hook;

FIG. 2 is a back elevational view of FIG. 1;

FIG. 3 is a right side elevational view of FIG. 1, a left side elevational view being a mirror image;

FIG. 4 is a top plan view of FIG. 1;

FIG. 5 is a bottom plan view of FIG. 1;

FIG. 6 is a top, front and right perspective view of FIG. 1; and, FIG. 7 is a top, back and left perspective view of FIG. 1.

The broken line showing a paint brush and portions of a paint bucket are for the purpose of illustrating environmental structure and forms no part of the claimed design.
